US0D1017096S

(12) **United States Design Patent** (10) Patent No.: **US D1,017,096 S**
(45) Date of Patent: ** Mar. 5, 2024

(54) **LIGHT EMITTING DIODE (LED) PENDANT LIGHT**

(71) Applicant: **Xiamen Longstar Lighting Co., Ltd.**, Fujian (CN)

(72) Inventors: **Dongwei Ge**, Fujian (CN); **Zhiyuan Yu**, Fujian (CN); **Cheng Zhang**, Fujian (CN); **Li Wei**, Fujian (CN)

(73) Assignee: **Xiamen Longstar Lighting Co., Ltd.**

(**) Term: **15 Years**

(21) Appl. No.: **29/895,767**

(22) Filed: **Jun. 26, 2023**

(30) **Foreign Application Priority Data**

Apr. 7, 2023 (CN) 202330183938.1

(51) **LOC (14) Cl.** **26-05**

(52) **U.S. Cl.**

(57) **CLAIM**

The ornamental design for a light emitting diode (LED) pendant light, as shown and described.

DESCRIPTION

FIG. 1 is a front elevation view of a light emitting diode (LED) pendant light showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof; and,

FIG. 8 is a second perspective view thereof.

1 Claim, 8 Drawing Sheets
